EMERGENCY EXTERIOR AIR CONNECTION UNIT FOR SUBMARINES

Filed Jan. 26, 1928

UNITED STATES PATENT OFFICE

JOHN P. AYER, OF PORTLAND, MAINE

EMERGENCY EXTERIOR AIR-CONNECTION UNIT FOR SUBMARINES

Application filed January 26, 1928. Serial No. 249,669.

My invention relates to an apparatus for use in connection with rescue work on sunken submarines and has among the objects, the provision of means for making an emergency air connection through the hull of a sunken submarine for supplying air to the interior thereof.

Other objects of this invention are: the provision of a novel structural arrangement for effecting air line communication through the hull of a submarine from the exterior to the interior thereof; to provide means for exteriorly effecting an air line connection to the interior of the hull of a submarine; and generally the provision of a novel and improved air line connection.

With these, and such other objects in view as will be apparent from the description, the invention resides in the novel construction, combination and arrangement of parts hereinafter described and claimed and illustrated in the accompanying drawings wherein is shown one practical, physical embodiment of the invention.

Figure 1 is a section through a portion of a submarine hull equipped with an inlet port cover and illustrating in elevation the specially designed wrench for manipulation externally of a submarine to remove the air port inlet covering means.

Figure 2 is a similar section through a submarine hull illustrating the application of an air supply unit to the air inlet port just before the closure means for the port has been removed.

Figure 3 is an elevation of the air port closure means taken internally of a submarine hull.

Figure 4 is a perspective of one element of the air port closure means.

Figure 5 is a perspective of an operating unit employed in connection with the air hose as shown in Figure 2.

The invention is shown in detail as applied to the hull 10 of a submarine and consists of an internal plate 11 rigidly attached to the interior face of the hull by a plurality of fastening elements such as rivets 12 and formed with an internal laterally extending neck 13 having an internal bore 14 therethrough and

communicating at its outer end with an air port 15 formed through the submarine hull. The neck 13 is both internally and externally threaded for the reception of closure means protecting the air inlet port against admission of water internally of the submarine. 55

This closure means comprises a plurality of units, consisting in the present embodiment of an internal cap 16 secured in position over the externally threaded portion of the neck 13 for closing the inner end of the air inlet bore 14, the cap having an internal annular shoulder 17 formed to seat in the inner opened end of the bore 14 to assist in closing the same when the cap is screwed down to fully closed position, as shown in Figure 1. The body of the cap 16 is provided on its inner face with a hexagonal socket 18 and on its external face with a tool engageable portion 19 whereby the cap may be removed or applied internally of the submarine if desired. 70

Cooperating with the cap 16 in forming the closure for the air port inlet 15 is an externally threaded plug 20 which is applied externally of the submarine hull or from the outer face of the plate 11 as the case may be, depending upon whether the closure assembly is an attached unit of the plate 11 before the plate is riveted in position or whether the closure means is applied after positioning of the plate. The plug 20 is threaded into the bore 14 in the neck 13 substantially filling the same and terminating adjacent the annular shoulder 17 carried by the internal cap 16. The outer end of the plug 20 is formed with an internally extending hexagonal socket to receive head 22 of a wrench 23 manipulated externally of the submarine by passing the head through the hull inlet 15 into engagement with the socket 21 of the plug 20, 80 as shown in Figure 1. 85

The air line connection as shown in Figure 2 comprises a casting 24 formed with a longitudinal air line bore 25 therethrough and which is controlled by manipulation of a valve 26 carried by the casting. The hull engageable end of the air line connection casting is tapered to an externally threaded end 27 adapted to be threaded into the neck 13 after the plug 20 has been removed there- 100

from. The opposite end of the casting has a threaded portion 28 for a conventional connection with an air hose, not shown, and laterally extending handles 29 are provided whereby the necessary rotation of the casting may be effected for screwing the end 27 into the neck 13.

The inner end 27 of the casting 24 is formed with a hexagonal socket for reception of the hexagonal connecting unit 30 which, as shown in Figure 2, extends between the inner end of the casting 24 and the cap 16, being seated in the hexagonal socket formed in the cap. It will be apparent that upon rotation of the casting 24 for completing its attaching engagement in the neck 13, the connecting unit 30 will cause a corresponding rotation of the cap 16 to complete the unscrewing thereof from its engagement over the external portion of the neck 13. A loop 31 is formed in the outer end of the connector unit 30 whereby the same may be attached by suitable means such as flexible wire, not shown, to some portion of the assembly of the casting 24 to prevent loss of the connector 30 when the same is being handled externally of the submarine. The attaching wire is, of course, removed before the connector 30 is inserted in position.

In the operation of the device, under normal operating conditions of a submarine, the cap 16 and the plug 20 are assembled in the position as shown in Figure 1 forming an effective closure for the inlet 15. The plug 20 not only assists the internal cap 16 in cooperating therewith as a closure, but also protects the interior threading of the bore 14 to facilitate attachment of the air line connection. It will be understood that each compartment of a submarine is provided with a plurality of air ports similar to that shown and described so that any desired number may be utilized to establish a free circulation of air through the compartment and for supplying food and water. In order to effect the air line connection, a diver operating externally of the submarine applies the wrench 23 to engage the hexagonal head 22 in the socket of the plug 20 manipulating the wrench to remove the plug from its seat. When this is accomplished, the connector unit 30 is removed from its loss preventing attaching means and inserted in the receiving socket in the attaching end 27 of the air line casting 24. If desired, after removal of the plug 20, the wrench head 22 may be applied in the socket 18 of the internal cap for starting the unscrewing of the cap. The attaching end 27 of the air line connection is then inserted through the bore 15 and threaded into the neck 13 in place of the plug 20, the connector 30 engaging in the cap socket 18 to rotate the cap simultaneously with the rotation of the casting 24 during its movement into the neck

13. The length of the thread in cap 16 is such that before the attaching end 27 of the air line connection has reached the internal limit of its travel, the cap 16 will have been entirely detached from its engagement over the exterior of the neck 13. When this connection has been completed, the valve 26 of course remaining closed during the operation, the air hose is connected at the end 28 and the valve 26 opened, after which a blast of air is sent through the line which will force the connector unit 30 out of its seat in the end 27 carrying the cap 16 with it into the interior of the submarine and freeing the air line. The steady supply of air is then sent through the connected line at any desired pressure.

While in this preferred embodiment of the invention I have illustrated and described certain details entering into the construction and operation thereof, I desire it to be understood that the invention is not to be limited thereto but that any desired changes may be made in the structural details as will fall within the scope of the invention as claimed.

I claim:

Emergency air connection means for submarines, comprising the combination with a hull structure having an air port therethrough, of a closure member detachably threaded thereover internally of the hull and having a polygonal socket in its external face, an air supply tube having a nozzle adapted for threaded attachment in and through said air port from the exterior of the hull, said nozzle having a polygonal socket provided in the walls of its bore, and a solid polygonal connecting plug seated in said nozzle socket for engagement in the socket of said closure member whereby to rotate said closure member for detachment thereof upon attaching rotation of the said nozzle, said connecting plug being dischargeable from said air supply unit by pneumatic pressure, and a control valve at the tube end of said nozzle.

In testimony whereof I affix my signature.

JOHN P. AYER.
